UNITED STATES PATENT OFFICE.

WALFRID WALLENTHIN, OF ATTLEBORO, MASSACHUSETTS, ASSIGNOR TO EDWARD EKSERGIAN, OF ST. LOUIS, MISSOURI.

CIGARETTE HOLDER.

Application filed November 7, 1921. Serial No. 513,331.

To all whom it may concern:

Be it known that I, WALFRID WALLENTHIN, a citizen of the United States, residing at Attleboro, county of Bristol, State 5 of Massachusetts, have invented a certain new and useful Improvement in Cigarette Holders, of which the following is a full, clear, and exact description, such as will enable others skilled in the art to which 10 it appertains to make and use the same, reference being had to the accompanying drawings, forming part of this application.

My invention relates to holders for cigarettes or cigars and consists in improvements upon the device shown in a joint application filed by Edward Eksergian and myself, Serial No. 496,068.

The object of my invention is to provide a better gripping element than disclosed in 20 the above-mentioned application and also to improve the stabilizing means for supporting the holder when it is laid upon a table top or similar surface.

In the accompanying drawings, which illustrate a selected embodiment of my invention,—

Figure 1 is a side view of my holder.

Figure 2 is a similar view taken at right angles to Figure 1 and showing the holder resting upon a supporting surface and holding a cigarette.

Figure 3 is a vertical section on line 3—3 of Figure 1, with the cigarette omitted.

Figure 4 is a transverse section on an enlarged scale taken on line 4—4 of Figure 1.

The body of my holder consists of a tubular section 1 partially closed at each end but provided with sufficient openings in its ends to permit the telescopic mounting in the tube of the operating member 2 and the gripping elements 3 in the lower and upper ends, respectively. The gripping elements are preferably made from a flat strip doubled at 4 on its transverse center and extending diagonally outwardly through 40 slots 5 in tube 1 and having each of its ends bent outwardly at 6, then inwardly as at 7, and downwardly as at 7^a, to form a gripping jaw and to extend rearwardly into the upper end of tube 1. This end of the tube 50 is crimped over as indicated at 8 with the crimped portions slightly enlarged at their ends to provide guiding openings 9 for the inturned ends 7^a of the jaw forming strip.

The operating member 2 consists of a 55 short length of tubing provided with spring seats 10 and 11 and slotted at 12 intermediate these seats. A coil spring 13 is slightly compressed between these seats and a pin 14 extends between two of the coils 60 of spring 13 and is anchored in the wall of tube 1. Upward movement of member 2 is resisted by the compression of spring 13 which tends to return the member and the gripping elements 3 which are attached 65 thereto to their normal position. Downward movement of member 2 is similarly resisted by spring 13 and also by the spring action of elements 3 against the wall of tube 1.

The lower end of member 2 is provided with a flat terminal portion 15 which is disposed at right angles to the space between jaws 7 or parallel to the axis of a cigarette held in the jaws. As a result of this construction, when the holder is laid upon a supporting surface as indicated in Figure 2, one of the projections 6 on an element 3 will support one end of the holder and space the cigarette held therein substantially 75 above the table, and the flat end 15 of member 2 will stabilize the holder in this position, these elements serving to prevent contact between the cigarette and the supporting surface.

The provision of slots 5 in handle 1 and the form of elements 3, as indicated, provides an easier spring-action for the gripping jaws and prevents an undesirable pinching of the cigarette which is likely 80 to result from the construction shown in the above-mentioned application. The provision of extension 6 on members 3 eliminates the necessity of providing a spacing element on the upper end of tube 1 and the 85 addition of the flat terminus 15 on the lower end of the holder enables the comparatively narrow flat surface of projection 6 to support the holder without the tendency to 90 tip over irrespectively of whether or not the cigarette is balanced in the holder.

My device is susceptible of many modifications in construction and I contemplate all such as fall within the scope of the following claims.

I claim:

1. In a cigarette holder, a hollow body, adjustable cigarette gripping jaws slidably

mounted in one end thereof, a jaw operating member slidable in the other end of said body for controlling the grip of said jaws, said member and either one of said jaws being adapted to cooperate to stably support a cigarette in a plane spaced from a table top or like surface upon which the holder is laid.

2. In a cigarette holder, a tubular body, 10 adjustable cigarette gripping jaws telescopically mounted in one end thereof, a jaw operating member telescopically mounted in the other end of said tube and provided with a flat terminal extending parallel with the 15 faces of said jaws, said member and one of said jaws being adapted to cooperate to hold a cigarette spaced from a supporting surface and parallel therewith.

3. In a cigarette holder, a tubular body, 20 open at one end and provided with a longitudinal slot adjacent to said end, a cigarette gripping jaw telescopically mounted in said body and comprising a flat element doubled on itself, the portions of the element extending through said open body end and said slot 25 respectively.

4. In a cigarette holder, a tubular body open at one end and provided with diametrically opposite longitudinal slots adjacent to 30 said end, cigarette gripping jaws telescopically mounted in said body and comprising flat elements, each doubled on itself, the portions of each element extending respectively through said open body end and through 35 one of said slots.

5. In a cigarette holder, a tubular body provided with diametrically opposite longitudinal slots adjacent to one end, cigarette gripping jaws telescopically mounted in said 40 body and comprising a flat strip doubled on

itself and extending through said slots near its bent portion with its ends redoubled and extending into the open end of said body.

6. In a cigarette holder, a tubular body, 45 open at one end and provided with a longitudinal slot adjacent to said end, a cigarette gripping jaw telescopically mounted in said body and comprising a flat element doubled on itself, the portions of the element extending through said open body end and said slot 50 respectively, the end of said tube being provided with a guiding opening for positioning the portion of said element extending therethrough axially of the body.

7. In a cigarette holder, a tubular body, 55 a flat strip extending diagonally and longitudinally through the side of said body, slideable therein and having its outer end bent to form an outwardly facing supporting projection and an inwardly facing cigarette 60 holding jaw.

8. In a cigarette holder, a tubular body, a strip extending diagonally and longitudinally through the side of said body near one 65 end, slideable longitudinally of said body and having its extended portion bent to form an outwardly facing supporting projection and an inwardly facing cigarette holding jaw, and an operating member for controlling said strip, and slidably mounted in the opposite end of said body and having a flattened end disposed in a plane parallel with the outer face of said supporting projection to cooperate with the latter to maintain a predetermined axial position of the holder 70 when laid upon a table or the like.

In testimony whereof I hereunto affix my signature this seventeenth day of October, 1921.

WALFRID WALLENTHIN.
